ASH DISPOSAL UNIT FOR FIREPLACE

Bernice E. Hagen, Los Angeles, Calif.

Application June 4, 1952, Serial No. 291,682

1 Claim. (Cl. 126—242)

This invention relates generally to receptacles and containers and more particularly to an ash receptacle. Specifically, the invention is concerned with an ash disposal unit for use in connection with a fireplace for receiving the ashes formed in the firebox due to burning of wood, charcoal or other materials.

Fireplaces constructed in the outside walls of homes and other buildings are usually provided with an opening in the firebox floor through which ashes may be swept to fall into the lower portion of the fireplace beneath the floor, such opening being normally closed by a suitable cover. In accordance with conventional fireplace construction, an outside clean-out door is provided by which the ashes may be periodically removed. It is well known that removal of the ashes through the clean-out door is a somewhat laborious task which is frequently complicated by the presence of shrubbery and vine growing alongside the fireplace and which must be climbed over by the person removing the ashes. For this reason, and the fact that the ashes are quite apt to be spilled and blown around during such removal, such conventional clean-out means are considered quite impractical. In certain instances, the fireplaces are installed in the inside walls of homes or other buildings so that the use of outside clean-out doors is impossible. In such cases, the ashes must be swept directly from the firebox floor into a dust-pan or other container which is carried outdoors to be emptied. This procedure obviously results in spilling the ashes in the house to create a very unsatisfactory condition.

It is therefore an important object of my invention to provide an ash receptacle which is so constructed and located in the fireplace as to adapt it to receive the ashes formed on the firebox floor and capable of being removed as a unit from within the building. By this provision, the ashes may be deposited and stored in the receptacle and the receptacle removed when it is full by simply lifting it from the firebox floor.

Another object of the invention is to provide an ash disposal unit which includes a rectangular frame installed as the rim of an opening formed in the firebox floor, a sheet metal box-like receptacle having a perimetrical flange at its upper end adapted to rest upon an inwardly directed flange of the frame to suspend the receptacle therefrom, and a two-part cover detachably mounted on the frame and normally overlying the top of the receptacle to close the same.

Another object is to provide an ash disposal unit in which the cover includes a member pivotally connected to the rearward end of the frame and resting in horizontal position against one or more lugs formed on the frame to normally close the rearward portion of the ash receptacle. A related object is to provide such a cover member which has rearwardly projecting hinge ears fitting within recesses at the rearward end of the frame and provided with holes for receiving transversely extending hinge-pins on the frame. By this pivot mounting, the rearward cover member may conveniently be pivoted

2

upwardly and then shifted bodily to disconnect its hinge ears from the pins to permit removal of the member.

Another object is to provide a cover having a forward member having a sliding engagement with the frame to 5 adapt this member to be slid in a rearward direction to close the forward end of the receptacle, and to be slid forwardly to uncover said forward end so that ashes may be swept from the firebox floor into the receptacle. In accordance with the present concept, the forward 10 portions of the sides of the frame are provided with tracks which are inclined upwardly toward the front end of the unit, the forward cover member having inclined grooves in its side edges for receiving the tracks so as to mount this member for forward and rearward sliding movement. By this provision, the forward cover member may be slid forwardly and upwardly so as to clear the edge of the floor opening in which the frame is installed. Thus, the forward cover member is wholly removable and the rear member is tiltable to adapt the ash 15 receptacle to be lifted from the floor opening for the purpose of emptying its contents.

A further object is to provide front and rear cover members which are adapted for economical manufacture as metal castings, these members being hollow on their 20 under sides to render them light in weight so that they may be easily handled.

A further object is to provide means for facilitating 25 pulling of the front cover member forwardly to open position, this means consisting of an upwardly extending curved lip providing a notch for receiving the hook of a fireplace tool by which the member may be pulled forwardly.

A still further object of the invention is to provide an 30 ash disposal unit, of the character referred to, which is adapted for installation in fireplaces of the types constructed in either inside or outside walls of a building, one which is relatively light in weight, yet sturdy in construction and durable in use, and one which is adapted for economical manufacture.

Further objects of the invention will appear from the 35 following description, and from the drawing, which is intended for the purpose of illustration only, and in which: Fig. 1 is a perspective view of my ash disposal unit, showing it installed in an opening of the firebox floor 40 of a fireplace;

Fig. 2 is a longitudinal sectional view, taken on line 45 2—2 of Fig. 1, the entire cover being shown in fully closed position over the ash receptacle;

Fig. 3 is a view similar to Fig. 2, showing the front cover 50 member slid forwardly to an extent to permit sweeping ashes into the receptacle from the firebox floor;

Fig. 4 is a cross-sectional view, taken on line 4—4 of Fig. 2; and

Fig. 5 is a fragmentary plan view of one of the rear 55 ward corners of the frame and rear cover member.

Referring to the drawing in detail, my ash disposal unit is adapted for installation within a well-like opening 8 formed in the firebox floor 9 of a fireplace 10, see Figs. 1 and 2. The floor opening 8 is provided with a relatively narrow shelf 11 at its upper end providing a seat upon which the lower flange 14 of a cast metal frame 15 rests. The frame 15 is of substantially Z shape in cross section, having a vertical web 16 projecting upwardly from the lower flange 14, and an upper horizontal flange 17 which is seated upon the firebox floor 9 and surrounding the opening 8.

As shown in Figs. 2 and 3, the upper flange 17 is omitted at the forward side of the frame, for the purpose to be presently explained. At the intersection of its sides and rear portion, the frame is provided with slots 20 and hinge-pins 21 projecting laterally into said slots, see Fig. 5. Substantially midway along the sides of

the frame 15, the lower flanges 14 are provided with lugs or rests 22. Adjacent their forward ends, the webs 16 at the sides of the frame have inwardly directed, longitudinally extending tracks 25 (Figs. 3 and 4), these tracks being inclined upwardly and forwardly toward the front end of the frame.

Adapted to be supported by the frame 15 is a sheet metal, box-like ash receptacle 26. As shown, the receptacle 26 has its upper edge portion folded laterally outward to provide a flange-like rim 27 which, when the receptacle is in place, rests upon the lower flange 14 to suspend the receptacle from the frame. While the ash receptacle 26 may be of any desired size, I have found that a receptacle of the approximate dimensions, 9" long x 14" wide x at least 14" high, provides adequate storage for ashes in the fireplace of a home. Preferably, the receptacle 26 is provided with pivoted handles 28 at its sides by which it can be conveniently lifted from the frame 15.

The ash disposal unit also has a cover for normally closing the open top of the ash receptacle 26. As herein shown, the cover includes a rear cover member or lid 30 and a front cover member or slideable closure 31. The member 30 takes the form of a cast metal rectangular plate, the under side of which is cored to provide a depending, perimetrical rim 32. At its rearward corners, the sides of the member 30 are extended rearwardly in hinge ears 33 which have holes for receiving the hinge-pins 21 so as to hingedly connect this cover member to the frame 15 and thus adapt the member to pivot from its horizontal position, in which it overlies the rearward portion of the receptacle to close the same, to a substantially vertical position, as indicated by the broken lines in Fig. 3, to open this portion of the receptacle. During normal use of the ash disposal unit, the cover member 30 assumes its said closed position, at which time the rim 32 at its forward end rests upon the lugs 22.

The front cover member 31 is also of plate-like form and has a cored-out lower portion providing a rearward flange 36 and side flanges 37, the lower edges of which are arcuate at the forward end of the member. The side flanges 37 are formed with inclined grooves 38 for receiving the inclined tracks 25 of the frame 15. By this connection, the front cover member 31 is normally supported in closed position with its rearward edge abutting the forward edge of the rear cover member 30. The member 31 may, however, be slid forwardly to open the forward portion of the ash receptacle 26 when it is desired to sweep ashes into the receptacle.

The cover member 31 may also be completely removed from the unit by sliding it forwardly as shown in Fig. 3, with the member riding along the inclined tracks 25. To facilitate such forward sliding movement, the cover member 31 is provided with a recessed ear 40 into which the hooked end 41 of a fireplace tool can be engaged. When the cover member 31 is in its closed position, a lateral flange 42 at the forward end thereof overlies the forward end of the frame 15 to take the place of the flange 17 which, as previously explained, is omitted at the forward portion of the frame.

When the cover member 31 is slid outwardly to open position, a stop projection 43 on its bottom strikes the web 16 to normally limit such forward movement, but since there exists considerable clearance between the grooves 38 and the tracks 25, the cover member may be tilted upwardly to cause its stop 43 to clear the front of the frame 15.

Assuming that the frame 15 has been installed in the opening 8 of the firebox floor 9, to assemble the unit in place the ash receptacle 26 is first lowered into the frame 15 as shown with its rim 27 resting upon the lower flange 14 of the frame. The rear cover member 30 then is pivotally connected to the frame 15 by holding the member in a vertical position and inserting its ears 33 into the slots 20, after which the member is

5 moved transversely to cause the pins 21 to enter the holes in the ears. The cover member 30 thus is hingedly connected and may be pivoted downwardly to horizontal position as shown in full lines in Figs. 1 to 3. The front cover member 31 is then placed in position with the forward ends of the tracks 25 entering the rearward ends of the grooves (Fig. 3), after which the member is slid rearwardly to the position shown in Figs. 1, 2 and 4.

10 With the ash disposal unit thus installed in the fireplace, it is located entirely beneath the fireplace floor 9 so as not to interfere with the fireplace grate, andirons or other equipment. Following the burning of wood, charcoal or other combustible material, the ashes formed on the fire-box floor may be conveniently disposed of by 15 simply sliding the front cover member 31 forwardly, as shown in Fig. 3, so as to open the forward portion of the receptacle 26, after which the ashes may be swept from the firebox floor into the receptacle. Following such deposit of the ashes in the receptacle, the cover member 31 is slid rearwardly to the position illustrated in Figs. 1 and 2 so as to close the receptacle.

20 This procedure is repeated, following each use of the fireplace and when it is observed that the receptacle 26 is nearly full, it is removed for emptying. Removal of the receptacle is accomplished by first sliding the cover member 31 forwardly to completely disengage it from the unit. The rear cover member 30 then is pivoted upwardly on the pins 21 to the position indicated by broken lines in Fig. 3. With the parts of the cover thus 25 fully opened, the ash receptacle 26 may be lifted vertically from the frame 15, by means of the handles 28. The receptacle is then carried to a place where the ashes are to be disposed of, after which the receptacle is returned to the fireplace and lowered into the frame 15. The cover member 30 is then swung down to its 30 closed position and the cover member 31 is slid into the frame 15 to close the forward end of the receptacle. Through the provision of the slots 20, pins 21 and ears 33, the cover member 30 is assembled on the frame 15 without the use of tools and fasteners, and the member 35 may be removed at any time by simply lifting and sliding it laterally in the slots 20 to free its ears from the hinge-pins so that the member can be lifted bodily from the unit.

35 40 45 While I have herein disclosed my ash disposal unit as embodied in a preferred form of construction, by way of example, it will be apparent that various modifications might be made in the structure and arrangement of the parts without departing from the spirit or scope of the invention. Consequently, I do not wish to be limited in this respect, but desire to be afforded the full scope of the appended claim.

I claim as my invention:

50 An ash disposal unit for use in connection with a fireplace having a firebox floor, comprising: an open frame 55 adapted to be fitted within an opening in the floor and having a shelf and lugs at its sides; a box-like receptacle fitting within the frame and having a perimetrical rim adapted to rest upon said shelf so as to suspend the receptacle from the frame; a first cover member pivotally mounted on the frame and adapted to be pivoted to one position to rest upon said lugs so as to overlie a first portion of the open top of the receptacle to close the same and to a second position to open said portion; and a second cover member slidably mounted on the frame and adapted to be slid to a first position to overlie a second portion of the open top of the receptacle to close the same with said first and second cover members in coplanar relation across the open top of the receptacle, and to a second position to open said second portion for the purpose of adapting said receptacle to receive ashes from the firebox floor through said second portion of the receptacle top, said first and second members being selectively removable from said frame, said first cover member having an outer transverse edge, said second

cover member having an inner transverse edge engageable with said outer transverse edge of said first cover member to limit inward sliding movement of said second cover member, said frame having inclined tracks at its sides, said second cover member having side flanges 5 provided with arcuate lower edges adapted to ride upwardly along an edge of said frame, said flanges having inclined grooves in their sides receiving said tracks to slidably mount the second cover member on said frame for sliding movement toward and away from said first cover member.
